CARBURETOR FOR INTERNAL COMBUSTION ENGINES

Harry F. Heisler, Black Hawk County, Iowa

Application September 10, 1956, Serial No. 42,887

Term of patent 3½ years

(Cl. D77-1)

Fig. 1 is a perspective view of my carburetor for internal combustion engines showing my new design therefor;

Fig. 2 is an end view;

Fig. 3 is a side view; and

Fig. 4 is a bottom view of my carburetor showing my new design.

I claim:

The ornamental design for a carburetor for internal combustion engines, substantially as shown.
